RESILIENT STOP FOR SCREW ELEVATORS

Carl Panter, Toledo, Ohio, assignor to Haughton
Elevator Company, Toledo, Ohio, a corporation
of Ohio

Application November 9, 1950, Serial No. 194,852

3 Claims. (Cl. 187—24)

1

This invention relates to screw driven elevators and in particular to a simple mechanism for safely stalling the drive motor of a screw driven elevator should the elevator car overrun its normal upper limit of travel.

It is customary in screw driven elevators to provide, on the bottom end of the elevating screw, a stop which by jamming against a rotating drive nut as the elevator reaches its extreme upper limit of travel stalls the motor. If the elevator operates at slow speed with a relatively low speed motor this jamming at the end of the travel is not particularly dangerous but nevertheless severely overloads parts of the mechanism and accelerates the wear on the drive mechanism. Furthermore, if the threads of the nut driving the screw are worn this sudden jamming at the end of the stroke may strip the threads in the nut thus robbing the elevator car of its support and allowing it to drop.

The principal object of this invention is to provide a preloaded resilient connection in the drive system for a screw-type elevator which preloaded resilient connection absorbs the kinetic energy of the drive motor and stalls the motor without seriously overloading any portion of the elevator drive system.

Another object of the invention is to provide a resilient connection, preferably preloaded, between an elevator support screw and an elevator car whereby the support screw may rotate against resilient restraint through a small angle when a stop on the bottom end of the screw jams against the drive nut.

A still further object of the invention is to provide a pair of preloaded helical compression springs that act between the arms of a cross-member mounted on an elevator support screw and fixed stops attached to an elevator car frame.

More specific objects and advantages are apparent from the following description of a preferred embodiment of the invention.

According to the invention an elevator screw that, on its lower end, is fitted with a stop adapted to jam against a rotary drive nut is, at its upper end, equipped with a resilient connection that permits the screw to rotate as the stop jams against the nut and by such rotation absorb the kinetic energy of the drive motor without overloading the elements of the drive train.

A preferred form of the invention is illustrated in the accompanying drawings.

In the drawings:

Figure I is an elevation, partly in section, of the drive mechanism of a screw-type elevator embodying the invention.

2

Figure II is an enlarged vertical section of the drive mechanism for the screw-type elevator.

Figure III is a fragmentary elevation of the connection between the elevator support screw and a portion of the elevator car frame.

Figure IV is a horizontal section as seen looking upwardly against the connection between the screw and car frame from the line IV-IV of Figure III.

10 These specific figures and the accompanying description are intended merely to illustrate the invention and not to impose limitations on its scope.

15 In a screw-type elevator embodying the invention an elevator car having a floor 1 is supported on a cross beam 2 that is guided in an elevator shaft (not shown) and in support on a screw threaded column 3 that extends through a gear box 4 and into a casing 5 extending downwardly through and beneath a foundation 6. A drive motor 7, mounted on a frame 8, has its armature shaft 9 connected to an input shaft 10 of the gear box 4. A brake drum 11 mounted on the shaft 9 cooperates with brake shoes 12 that are actuated by a solenoid 13. The brake shoes 12 are spring set and are applied to the brake drum 11 whenever the power is taken off the motor 7. A protective (or dust shield) 14 extends over the motor 7 and the brake mechanism.

10 Referring now to Figure II the screw threaded 30 elevator support column 3 extends through an internally threaded drive nut 15. The nut 15 is supported on a tapered rolling bearing comprising an outer race 16 mounted in a cylindrical insert 17 of the gear housing 4 and an inner race 18 mounted on a cylindrical portion of the nut 15 and held in place by keys 19 which are secured by a cap 20. Tapered roller bearings 21 interposed between the inner and outer races support the elevator car and its load while permitting the nut to turn in raising or lowering the elevator car.

35 The lower portion of the nut 15 is journaled in a cylindrical bore 22 of a boss 23 raised from the floor of the gear box 4.

40 A worm wheel 24 formed integrally with the nut 15 engages a worm 25 mounted on the input shaft 10 of the gear box 4. Rotation of the motor thus drives through the worm 25 and worm wheel 24 to rotate the nut 15 and thus raise or lower the elevator car.

45 A flanged steel collar 26 loosely sleeved over the end of the screw threaded column 3 is carried adjacent the lower surface of the cylindrical nut 55 15 with its flanged portion resting on shoulders

27 formed by a reduced diameter portion of the bore 22. The steel collar 26 is jammed against the lower surface of the rotatable drive nut 15 as a heavy cylindrical pin 28 mounted in and projecting laterally from the lower end of the threaded column 3 engages the flanged collar 26 at the upper limit of travel of the elevator car. The steel collar 26 is interposed between the heavy cylindrical pin 28 and the lower surface of the nut 15 to prevent the pin from gouging the nut as the motor is stalled by jamming of the drive mechanism at the upper limit of travel.

Referring now to Figures II, III and IV the upper end of the threaded elevator support column 3 is engaged in a resilient connection attached to the cross member 2 of the elevator car frame. This connection comprises a plate 29 that is attached to the cross member 2 and that has fixed downwardly directed lugs 30. A cross arm 31 mounted on a pin 32 extending through the upper end of the threaded support column 3 has its arms 33 in abutting relation to the sides of the downwardly directed lugs 30 such that the arms are urged against the abutments during downward travel of the elevator.

The arms 33 are resiliently held against the lugs 30 by a pair of helical compression springs 34 and the lugs 30. Tightening of nuts 36 compresses the springs 34, held between the heads 37 of the bolts 35 and the arms 33 of the cross member 31 to force the arms 33 against the lugs 30 so as to preload the springs and resiliently hold the arms 33 against the lugs 30.

A second plate 38 having a central hole to accommodate the threaded support column 3 is located immediately below the cross member 31 and the lugs 30 and is attached to and spaced from the first plate 29 by a plurality of threaded studs 39 and spacers 40. The plate 38 prevents the support column 3 from being disengaged from the first plate 29 should the elevator car stick in the hatchway or strike buffers at the bottom of the hatchway before the support column 3 itself is stopped.

In this arrangement, during upward travel of the elevator, the support column 3 is held from turning relative to the elevator car by the preload force of the compression springs 34. Should the elevator overrun its upper landing position the heavy cylindrical pin 28 at the lower end of the column drives the steel collar 26 against the nut 15 thus jamming the screw 3 in the nut 15. During deceleration of the motor 7 the nut 15 continues to turn thus turning the screw 3 against the force of the springs 34. The force required from the drive motor 7 to overcome the resistance of the springs 34 is much greater than the available motor torque so that the motor is quickly stalled. The kinetic energy stored in the motor armature is absorbed partly by the springs 34, 60 partly by friction between the upper surface of the cross member 31 and the lower surface of

the first plate 29, and partly by friction between the worm 25 and the worm wheel 24. The friction forces, however, are small enough so that upon reversal of the motor 7 the column 3 rotates back to its normal position and the jam between the nut 15 and the threads on the column 3 is released.

This arrangement of a resilient connection in an elevator drive system prevents extremely high 10 jamming forces that would occur if the motor were suddenly stopped when the screw jams at the upper end of its travel. This elimination of the extremely high shock forces reduces the amount of wear to be expected and the danger of 15 shearing the threads in the nut 15.

Various modifications in the detail of the resilient member of the drive system may be made without departing from the spirit and scope of the invention.

20 Having described the invention, I claim:

1. In an elevator, in combination, an elevator car frame, a screw threaded column supporting the car frame, a base, a nut threaded on the column and journaled in the base, means for 25 driving the nut, a member fixed to the bottom of the column and engageable with the nut at the end of the upward travel of the elevator frame, a cross member on the top of the column, stops on the frame engaging the cross member, and 30 resilient means for holding the cross member against the stops during upward travel of the elevator and absorbing the shock of the nut driving means when said member engages the nut.

2. In an elevator, in combination, an elevator car frame, a screw threaded column supporting the car frame, a base, a nut threaded on the column and journaled in the base, means for driving the nut, a member fixed to the bottom of the column and adapted to engage the nut, a cross member fixed to the upper end of the column, a pair of stops fixed to the car frame and engaging the cross member, a pair of springs urging said cross piece against the fixed stops, and means for supporting the springs.

3. In an elevator, in combination, an elevator car frame, a screw threaded column for supporting the frame, a base, a nut threaded on the column and journaled in the base for supporting the column, a motor operatively connected to the nut, means on the bottom of the column to lock with the nut when the column reaches its upper limit of travel, a cross arm on the upper end of the column, a pair of stops on the frame, bolts extending through said stops and the adjacent ends of the cross arm, and springs sleeved on said bolts for urging the cross arm against the stops and permitting said column to rotate against the force of the springs when said means locks the column to the nut.

CARL PANTER.
